FIG. 6

FIG. 7

FIG. 1 is a perspective view of an exercising table, showing the new design;

FIG. 2 is a side elevational view thereof taken from the right of FIG. 1;

FIG. 3 is a side elevational view thereof taken from the left of FIG. 1;

FIG. 4 is a front elevational view thereof;

FIG. 5 is a rear elevational view thereof;

FIG. 6 is a top plan view thereof; and

FIG. 7 is a bottom plan view thereof.

I claim:

The ornamental design for an exercising table, as shown.
